GAME APPARATUS

Taliesen A. Lloyd, Los Gatos, Calif.

Application May 22, 1939, Serial No. 275,025

6 Claims. (Cl. 273—136)

The present invention relates to game apparatus and more particularly to a game which is playable upon a board over which play pieces, such as checkers or the like, are moved successively by opposing players.

An object of the invention is to provide a new and novel game apparatus in which play pieces are moved successively by opposing players over a game board having changeable characteristics in which the movements of the play pieces of the respective players are determined by the changed characteristic of the board.

Another object of the invention is to provide a game apparatus having play piece supporting areas from one to the other of which playing pieces are adapted to be moved by opposing players in which the character of said areas may be periodically changed to vary the playable path for the play pieces.

Another object of the invention is to provide a game board having a checkered surface over which checkers are adapted to be moved as the game progresses and in which the character of the checkered surface is changeable to control the possible course of movement for the playing pieces thereupon.

A further and more general object of the present invention is to provide a game apparatus in which playing pieces are moved upon a game board in a manner following that obtaining in checkers and/or chess and in which the character of the game board may be changed during the course of the game without disturbing the play pieces to thereby render the possible movements of the opposing play pieces of an uncertain nature as each player is called upon to make his play.

For a better understanding of the invention reference should be had to the following description taken in connection with the accompanying drawing wherein there is shown by way of illustration and not of limitation preferred embodiments thereof.

In the drawing:

Figure 1 is a perspective view showing a game board constructed in accordance with one embodiment of the invention.

Figure 2 is a perspective view showing a play piece in the form of a conventional checker.

Figure 3 is a vertical sectional view taken along line III—III of Figure 1 looking in direction of arrows.

Figure 4 is a plan view of an element of the game board shown in Figure 1 of the drawing.

Figure 5 is a fragmentary view showing a de-

tail of construction of the device illustrated in Figures 1 and 3 of the drawing.

Figure 6 is a fragmentary perspective view showing a modified form of the invention, and

Figure 7 is a perspective view of an accessory, such as may be used with the embodiment of the invention illustrated in Figure 6 of the drawing.

Reference is now made to Figures 1, 2 and 3 of the drawing for a detailed description of the invention. As shown in these figures of the drawing, the invention in its simplest form contemplates a game board, designated by the numeral 10, upon the surface of which there is formed a plurality of adjacent outlined areas 11 from one to the other of which a play piece, not shown, is adapted to be moved in accordance with predetermined rules as the game progresses.

Associated with the game board 10 there is a rotatable disc 12 that is adapted to be turned or spun periodically at predetermined intervals 20 throughout the game and upon which there is formed, as will hereinafter appear, suitably arranged designating characters that are adapted to be related with the outlined areas upon the game board 10 to thereby control the directions 25 in which the playing pieces of the players may be moved. The rotatable disc 12 is preferably mounted upon a shaft 13 that extends vertically through the center of the game board 10 where a spinning knob 14 at the upper end thereof may 30 be turned by the players to thus impart a spinning movement to the disc 12. In order that the designating characters upon the disc 12 may be viewed from the top of the board to determine the character designation of the areas containing no playing pieces, each of the outlined areas 11 is provided with a central aperture 15

that forms a sight opening therein. The apertures 15 are here shown as square in outline, but it is to be understood an aperture of any suitable 35 shape, as for example a round hole will serve equally well. It is also contemplated that the outlined areas 11 may be formed by suitably etched outlines upon a sheet of glass or other transparent material so that the rotatable disc 40 12 with its area designating characters will be clearly visible through the game board 10.

As will be clear from Figure 3 of the drawing, the shaft 13 with the rotatable disc 12 forms a unit which may be spun like an ordinary top by 50 means of the spinning knob 14. When such a spinning motion is imparted to the shaft 13 the rotatable disc 12 will travel beneath the apertures 15 and as a result different area designating characters upon the disc 12 will be visible through the 55

apertures 15 as will be determined by the position in which the rotatable disc 12 comes to a stop. In Figure 4 of the drawing the rotatable disc 12 is shown as having a checkered area similar in dimensions to the playing surface formed by the outlined areas 11 upon the game board 10. The checkered areas, as here shown, comprise a series of alternately arranged red and blue squares, respectively designated by the numerals 16 and 17. With this arrangement it will be noted that by having an even number of squares in each horizontal and vertical line of the checkered surface, the squares at the opposite ends of each line are of a different color and consequently upon each revolution of the rotatable disc 12 there will be produced two changes in the color that will show through the apertures 15 of any one of the outlined areas 11 upon the game board 10. Therefore, since the position in which the rotatable disc 12 will come to a stop is uncertain, there will be introduced into the game an element of chance that will determine the possible direction in which the playing pieces of each player may be moved after each spinning of the rotatable disc 12.

In order to insure a stopping of the rotatable disc 12 after each spinning thereof, with the characters thereupon in coincidence with the outlined areas 11 upon the game board 10, the shaft 13, as shown in Figure 5 of the drawing, also carries a four pointed hub 18 with which a suitable stopping means 19 is adapted to cooperate. The hub 18 has the shape of a mutilated square and the stopping means 19 is shown as a spring having a configuration at its free end which is comparable to the surface of the hub 18. With this arrangement it will be seen that when the rotatable disc 12 and the hub 18 are set in rotation, as by the application of a spinning force to the shaft 13 by means of the knob 14, the spring 19 will ride over the four points of the hub 18 as long as the rotatable disc 12 retains sufficient momentum to overcome the stopping action of the spring 19. However, when the rotatable disc 12 loses its momentum the spring stop 19 will operate to bring the rotatable disc 12 to rest in one of four positions where either a red or a blue designating color will be in coincidence with each of the outlined areas 11 upon the game board 10.

For the purpose of describing the operation of a game apparatus constructed in accordance with the embodiment of the invention illustrated in Figures 1 to 5 of the drawing, it will be assumed that two players, A and B, located respectively at opposite points upon the game board 10, are each provided with twelve playing pieces of the type shown in Figure 2 of the drawing, it being understood that the twelve playing pieces of each player are of a different color. For example, the player A may be provided with twelve pieces that are blue in color and which are playable only upon the outlined areas 11 which are designated by a blue square upon the rotatable disc 12 as viewed through the apertures 15 of said outlined areas, and that the player B is equipped with twelve red playing pieces that are playable only upon outlined areas 11 which are characterized by a red designating area upon the rotatable disc 12 as viewed through the apertures 15 of these outlined areas 11. With this equipment each of the players will start with his respective playing pieces positioned upon the twelve outlined areas 11 that are encompassed in heavier outlined markings 20 and 21 which constitute the starting

field of the playing pieces. Like the game of checkers or chess, the four outermost squares of each of the outlined areas 20 and 21 may be considered to constitute a king row, which when entered by an opposing player, will convert his playing piece into a king piece that may be moved either backward or forward, it being understood that during all prior moves the playing pieces of each player will be movable only in a forward and sidewise direction either diagonally or at right angles to the squares in which it at the time reposes. To start the play, the operator A, whose playing pieces are blue and are playable only upon blue squares, will grasp the spinning knob 14 and cause the rotatable disc 12 to spin and come to a stop. After such a spinning of the rotatable disc 12, the player A will move one of his pieces to an open blue outlined area 11. After the player A has made his move, the player B will spin the rotatable disc 12 in the manner followed by the player A and will then move one of his red playing pieces to a red outlined area 11, as determined by the position in which the rotatable disc 12 comes to a stop. This procedure will be followed successively throughout the game, each player in his turn spinning the rotatable disc 12 before moving one of his playing pieces.

While the movements of the playing pieces of the players A and B have been described above as limited to squares of different colors, it is conceivable that the game may be played by limiting the moves of the playing pieces of each of the players to outlined areas 11 of the same character, as determined by the position in which the rotatable disc 12 stops. It is to be also understood that instead of color designations, the rotatable disc 12 may carry numbers, letters or words, as for example in the latter case the words "Stop" and "Go" may be alternately arranged in the horizontal and vertical rows of the rotatable disc 12.

Reference is now made to Figures 6 and 7 of the drawing for a description of a further embodiment of the invention. As here shown, the game board, designated by the numeral 22, is constructed in a manner similar to a conventional checkerboard in that it has outlined playing piece areas 23 which cover substantially the entire surface of the game board 22. The outlined areas 23 of this game board, like the areas 11 upon the game board 10, are each provided with sight apertures 24 through which an indicia carrying member 25 is visible. The member 25 is mounted beneath the game board 22 so that it may be moved between two positions with a sliding movement by means of an operating handle 26. The upper surface of the movable member 25 is here shown as having a checkered surface formed by alternately arranged red and blue squares, respectively designated by the numerals 27 and 28. The arrangement of the red and blue squares 27 and 28 of the checkered surface upon the movable member 25 is such that when it is in its outermost position, as illustrated, the respective outlined areas 23 upon the game board will provide a playing surface having a predetermined color arrangement, and when the movable member 25 is in its innermost position the outlined areas 23 will be respectively of a different color and will thus provide a playing surface having a different color arrangement. For example, when the movable member 25 is in its outermost position, the squares in the bottom row, reading from left to right, will be design- 75

nated as blue, red, blue, etc., and when the movable member 25 is in its innermost position, the color designation of these squares will be reversed.

5 In order to maintain the element of chance in the game, as contemplated by the invention, it is proposed to provide each game board of the latter type with a means for determining the position into which the movable member 25 is to be at the time when a player is called upon to move a play piece. In Figure 7 there is shown one form of such a device which comprises a card 29 having a spinnable arrow or pointer 30 mounted thereupon, the arrow 30 being adapted to co-operate with suitably marked areas upon the card 29 which will indicate, for example, whether the next move of a player is to be made with the movable member 25 in its innermost or outermost position. As alternative forms for this accessory, it is contemplated that a spinning top having flat sides with proper indicating indicia might be substituted for the card 29 upon which the pointer 30 is mounted, or as a further alternative form, it is conceivable that an ordinary dice-like member having proper indicating indicia upon its six sides might be used for the purpose of determining into which position the movable member 25 is to be at the time of the next move by a player.

30 With a game board of the last described type it will be understood that at the start of the game the playing pieces may be arranged in lines extending entirely across the board and while in the preferred arrangement it is contemplated that the playing pieces may be placed upon adjacent squares at the start of the game, it is also conceivable that the game may be started with playing pieces arranged only on alternate squares of the same color, as is the case with checkers. A further feature of the present invention is that the movement of the playing pieces may be limited to a diagonal path or to a straight forward or sidewise path or in fact to any combination of these paths. In other words, the paths of movement of the playing pieces of any particular player may be determined by rules established or agreed upon at the beginning of the game. After the game has progressed to a point where the opposing playing pieces come into proximity with each other it is also contemplated that the opposing players in moving their playing pieces will, in attempting to reach the king row of his opponent, also endeavor to jump and remove from the board as many of his opponent's playing pieces as possible, in much the same manner as in the game of checkers. A variation of this game may also be provided by establishing rules that will permit the removal of an opponent's man by moving a playing piece to a square occupied by an opponent's playing piece, as in chess.

60 From the above it will be seen that this invention provides a game apparatus upon which many complicated and interesting games may be played in which skill, comparable to that applied in playing checkers or chess, is required and in which at the same time there will also be introduced an element of chance tending to defeat and/or at least make difficult the following through of any definite line of play on the part 70 of the competing players.

While I have, for the sake of clearness and in order to disclose the invention so that the same can be readily understood, described and illustrated specific devices and arrangements, I desire 75 to have it understood that this invention is not

limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is—

1. In a game apparatus, the combination of a play piece supporting surface having areas thereupon from one to the other of which a playing piece is adapted to be moved, the movements of the playing pieces of each player being limited to areas of a predetermined character, a disc rotatably mounted below and visible through said play piece supporting surface having different area designating characteristics formed thereupon and arranged when in different positions to coincide with the areas upon said play piece supporting surface, and means for spinning said disc to bring the same or different designating characteristics thereupon into register with the areas upon said surface when said disc stops spinning, whereby the possible movements of the 25 playing pieces of each player in his turn will be determined by the point at which said disc comes to rest with respect to the areas upon said play piece supporting surface.

2. In a game apparatus, the combination of a play piece supporting surface having areas thereupon from one to the other of which a playing piece is adapted to be moved, the movements of the playing pieces of each player being limited to areas of a predetermined character, a disc rotatably mounted below and visible through said play piece supporting surface having different area designating characteristics formed thereupon and arranged when in different positions to coincide with the areas upon said play piece supporting surface, means for spinning said disc to change the positions of the designating characteristics thereupon with respect to the areas upon said surface, and means associated with said disc adapted after each spinning to bring it to a stop 45 with the designating characteristics thereupon in register with the areas upon said play piece supporting surface, whereby the possible movements of the playing pieces of each player will be determined after each spinning of said disc 50 by the point at which said disc is stopped with respect to the areas upon said play piece supporting surface.

3. In a game apparatus, the combination of a game board having a surface with outlined areas thereupon from one to the other of which a playing piece is adapted to be moved, said game board also having sight openings formed in each of said outlined areas through which a color providing means located therebelow may be viewed, the movements of the playing pieces of each player being limited to areas of a predetermined character as determined by character indications visible through the individual sight openings of said areas, and a movable member mounted below and visible through the sight openings formed in the outlined areas of said game board having two different alternately arranged character indications thereupon adapted when in one position to coincide with the sight openings of 60 said game board and establish a predetermined character for each of the outlined areas upon said playing surface and when in another position to establish a different predetermined character for each of said outlined areas, whereby the 70 75

possible movements of the playing pieces of each player upon said surface will be determined by the character established for said areas by movements of said movable member.

6. In a game apparatus, the combination of a game board having a surface with outlined areas thereupon from one to the other of which a playing piece is adapted to be moved, said game board also having apertures formed in each of 10 said outlined areas through which a color providing means located therebelow may be viewed, the movements of the playing pieces of each player being limited to areas of a predetermined color as viewed through the individual apertures thereof, a vertically disposed shaft extending upwardly through the surface of said game board and having means at its upper end whereby it may be caused to spin, and a member carried by said shaft below said game board surface and visible 15 through the apertures formed in the outlined areas thereof, said member having a checkered surface of contrasting colors adapted when stopped in one position to coincide with the apertures of said game board and establish one checkered color arrangement for the outlined areas upon said playing surface and when stopped in another position to establish a different 20 checkered color arrangement for said outlined areas upon said playing surface and when stopped in another position to establish a different checkered color arrangement for said outlined areas, whereby the possible movements of the playing 25 pieces of each player upon said surface will be determined by the colors established for said outlined areas by a spinning and stopping of said movable member.

5. In a game apparatus, the combination of a game board having a surface with outlined areas thereupon from one to the other of which a playing piece is adapted to be moved, said game board also having apertures formed in each of 30 said outlined areas through which a color providing means located therebelow may be viewed, the movements of the playing pieces of each player being limited to areas of a predetermined color as viewed through the individual apertures thereof, a vertically disposed shaft extending 35 upwardly through the surface of said game board and having means at its upper end whereby

it may be caused to spin, a member carried by said shaft below said game board surface and visible through the apertures formed in the outlined areas thereof, said member having a checkered surface of contrasting colors adapted when stopped in one position to coincide with the apertures of said game board and establish one checkered color arrangement for the outlined areas upon said playing surface and when stopped in another position to establish a different 10 checkered color arrangement for said outlined areas, whereby the possible movements of the playing pieces of each player upon said surface will be determined by the colors established for said outlined areas by a spinning and stopping 15 of said movable member, and means cooperating with said shaft adapted to stop said member in any one of a number of positions with its checkered surface in coincidence with the apertures of said outlined areas, whereby the checkered 20 color arrangement of the outlined areas of the game board will be determined by the position in which said member is stopped.

6. In a game apparatus, the combination of a checkered board over which playing pieces may be moved having conventional squared outlines thereupon with apertures formed in each of said squared outlines through which a square designating color is visible, the movements of the playing pieces of each player being limited to areas of a predetermined color as viewed through the individual apertures of said squares, and a slideable member mounted below said board having a checkered surface of contrasting colors visible through the apertures in each of said squared 30 outlines, said slideable member being movable between two positions and adapted when in one position to establish a predetermined contrasting color for the adjacent squares of said board and when in another position to provide an opposite 35 contrasting color arrangement for the outlined squares of said board, whereby the color arrangement of the outlined squares upon said surface will be changed with each movement of said slideable member.

TALLESEN A. LLOYD.
